(57) CLAIM

The ornamental design for a mount, as shown and described.

DESCRIPTION

FIG. 1 is a front perspective view of a mount, according to the present design;

FIG. 2 is a front side view thereof;

FIG. 3 is a back side view thereof;

FIG. 4 is a top view thereof;

FIG. 5 is a bottom view thereof;

FIG. 6 is left side view thereof; and,

FIG. 7 is a right side view thereof.

The broken lines in the Figures represent a logo trademark and form no part of the claimed design.

1 Claim, 7 Drawing Sheets
